(74) *Attorney, Agent, or Firm*—Bryan Cave LLP

(57) **CLAIM**

We claim the ornamental design for a computer mouse, as shown and described.

DESCRIPTION

FIG. 1 is a front, top, right isometric view of the computer mouse;

FIG. 2 is a back, top, left isometric view thereof;

FIG. 3 is a top view thereof;

FIG. 4 is a bottom view thereof;

FIG. 5 is a front view thereof;

FIG. 6 is a back view thereof;

FIG. 7 is a left view thereof; and,

FIG. 8 is a right thereof.

The broken lines in the drawings are for illustrative purposes only and form no part of the claimed design.
